UNITED STATES PATENT OFFICE.

HAROLD N. CARPENTER, OF WOODFORD, VERMONT.

FOUNTAIN-PEN-FILLING AND INK-PACKAGING DEVICE.

1,125,470.

Specification of Letters Patent.

Patented Jan. 19, 1915.

Application filed February 12, 1912. Serial No. 677,025.

To all whom it may concern:

Be it known that I, HAROLD N. CARPENTER, a citizen of the United States of America, residing at Woodford, in the county of Bennington and State of Vermont, have invented a new and useful Fountain-Pen-Filling and Ink-Packaging Device, of which the following is a specification.

My invention relates to ink containers provided with means for filling fountain pens or similar objects.

Some of the objects of my invention, are to provide an inexpensive, simple, cleanly, and rapidly operating device for filling pens of the class described, and one which at the same time serves as a safe ink receptacle or package, in which ink may be transported conveniently. I attain these, and other objects by the means described and specified fully hereinafter, and illustrated in the accompanying drawing, in which like symbols of reference refer to like parts throughout the respective views.

Figure 1, is a vertical center section of the device with a pen inserted preparatory to filling. Fig. 2, is a similar section of the throat member, forming a part of the complete device. Fig. 3, is an elevation of the stopper or closure for the whole.

Referring to the drawings, 1 is the inelastic body portion of the receptacle or container opened at both ends, which may be made of glass or other suitable material such as is not injuriously affected, or will not injuriously affect the ink, and which possesses the necessary strength and other qualities of a desirable container and transporter. It is preferably though not necessarily of cylindrical form. Its top is contracted to form a neck 2 and a flange or beading 3 encircles the top of the neck, and a similar flange 4 encircles the bottom of the whole.

5 is an elastic and compressible member of suitable material having a general dome shape, and projecting into the body portion of the receptacle, the outer edge of which is preferably formed with a turned up rim 6, and is adapted to overlap the bottom of the receptacle 1, and the flange or beading 4, above and around which it is secured by suitable binding or clamping means 7. The dome shaped portion of the elastic member projects into the interior of the receptacle, and the whole is made air tight by the binding means above mentioned. Depending from the dome shaped portion is a tongue or

finger piece 8, of such length so as to permit it to be manipulated in such a way as to oscillate the elastic member within the receptacle 1.

9 is an elastic member which is formed so as to constitute a cap or cover, the walls 10 of which overlap the neck 2 of the receptacle, from which it is prevented from slipping by the flange or beading 3. It is obvious that it may be further rendered more secure by binding it below the flange if desired. The member 9 is further formed or provided with a tubular or funnel shaped portion 11 depending therefrom and into the neck 2, and is so shaped that the opening 12 is adapted to be closed air tight by the insertion of the pen to be filled.

13 is a stopper, adapted, when the filler is not in use, to close the opening 12.

As a pen filler the operation of the device is as follows: On removing the stopper 13, the pen is inserted in the funnel 11, without removing the nibs portion from the barrel, and passes through the opening 12 into the interior of the receptacle, forming an air tight contact with the funnel 11. The filler and pen are next inverted, and the elastic member 5, is oscillated by means of the tongue 8, until the pen is filled. The oscillation of the elastic member, when in this position, sucks the air out, and forces the ink into the pen, without the delay and annoyance of unscrewing and replacing the pen portion with the consequent uncleanliness.

I am aware that prior to my invention, pen filling devices which exhaust the air from the inserted pen, and subsequently fill it with the contained ink, have been devised, I therefore do not claim such a device broadly, but on the other hand I do not limit myself to any particular size, shape, proportion or material, for my improved device as above shown and described may be departed from in those respects without departing from my invention.

Where I have used the words "fountain pen" I mean to include by that term any reservoir pen or pencil such as a stylographic pen, or other inking device having a reservoir from which it is fed.

It is evident that the oscillation of the elastic member 9 produces a distention or extension or enlargement of the interior volume of the receptacle, when withdrawn from the interior of the receptacle, and conversely diminishes or reduces the interior

volume when compressed or allowed to retract by its own elasticity.

What I claim and desire to protect by Letters Patent is,

- 5 1. A fountain pen filling device comprising a receptacle having an inelastic body portion, and an elastic tube secured to one end of said body portion and adapted to receive the fountain pen, and an elastic and compressible member having a manipulating tongue secured to the other end of the body portion.
- 10 2. A fountain pen filling device, comprising a receptacle having at one end elastic means adapted to receive a fountain pen, and an elastic member secured to the other end of the receptacle, and means depending therefrom for manipulating said elastic member.
- 15

3. A fountain pen filling device, comprising a receptacle having at one end elastic means adapted to receive the fountain pen, and an elastic member secured to the other end of the receptacle and projecting thereinto, and means depending therefrom for manipulating said elastic member.

4. A fountain pen filling device, comprising a receptacle having at one end elastic means adapted to receive a fountain pen, and an elastic member secured to the other end of the receptacle, said member being provided with means for retracting said member away from the receptacle so as to increase the interior volume of the latter.

HAROLD N. CARPENTER.
